US0D1069306S

(12) **United States Design Patent** (10) **Patent No.:** **US D1,069,306 S**
(45) **Date of Patent:** **** Apr. 1, 2025**

(54) **CLEANING MOP**

(71) Applicant: **Xiaojun Shen**, Jiaxing (CN)

(72) Inventor: **Xiaojun Shen**, Jiaxing (CN)

(**) Term: **15 Years**

(21) Appl. No.: **29/902,395**

(22) Filed: **Sep. 12, 2023**

(51) LOC (15) Cl. **07-05**

(52) U.S. Cl.

USPC **D32/51**

(58) **Field of Classification Search**

USPC D32/15, 17, 40, 50, 51, 52

CPC A47L 13/10; A47L 13/20; A47L 13/24;

B32B 2432/00; Y10S 15/09; Y10S

493/942

(57) **CLAIM**

The ornamental design for a cleaning mop, as shown and described.

DESCRIPTION

FIG. 1 is a front perspective view of a cleaning mop, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is its open state diagram.

1 Claim, 8 Drawing Sheets
